CLAIM

The ornamental design for an implantable cardiac monitor, as shown and described.

DESCRIPTION

FIG. 1 is a front, right side, perspective view of a first embodiment of an implantable cardiac monitor according to the present disclosure.

FIG. 2 is a front view of the implantable cardiac monitor of FIG. 1.

FIG. 3 is a right side view of the implantable cardiac monitor of FIG. 1.

FIG. 4 is a left side view of the implantable cardiac monitor of FIG. 1.

FIG. 5 is a front, right side, perspective view of a second embodiment of an implantable cardiac monitor according to the present disclosure.

FIG. 6 is a front view of the implantable cardiac monitor of FIG. 5.

FIG. 7 is a right side view of the implantable cardiac monitor of FIG. 5; and,

FIG. 8 is a left side view of the implantable cardiac monitor of FIG. 5.

The broken lines in the Figures illustrate portions of the article that form no part of the claimed design.

1 Claim, 4 Drawing Sheets

Related U.S. Application Data

continuation of application No. 14/204,227, filed on Mar. 11, 2014, now Pat. No. 11,311,312.
